COMMUNICATION ANTENNA

Marvel W. Scheldorf, Palos Heights, Ill., assignor to Andrew Corporation, Chicago, Ill., a corporation of Illinois

Continuation of application Ser. No. 534,569, Sept. 15, 1955. This application May 12, 1958, Ser. No. 735,090

16 Claims. (Cl. 343—800)

This invention relates to antennas, and more specifically to a novel construction for the type of antenna employing a rigid self-supporting conducting structure such as a mast or tower as a radiating element thereof. This application is a continuation of application Serial No. 534,569, filed September 15, 1955, now abandoned.

In one type of antenna, designed for maximizing radiation normal to the antenna and minimizing radiation in the direction of extension of the antenna, the signal is fed directly to the radiator, which has a length of a substantial number of half wavelengths, and radiation from alternate half-wavelengths is suppressed, thus producing the desired concentration of radiation perpendicular to the antenna and eliminating the lobes in the radiation pattern in undesired directions which are produced in the absence of such suppression. Radiation suppressors of high efficiency for such purposes are described in the co-pending application of the same inventor, Serial No. 545,662, filed November 8, 1955, now abandoned, and in U. S. Patent 2,852,774. However, the particular form of suppressor therein illustrated is poorly suited for employment on large radiating elements such as vertical polygonal towers. It is accordingly an object of the present invention to provide an improved form of radiation suppressor capable of simple and economical construction and mounting for the suppression of radiation from particular portions of radiating elements, particularly where such elements are of large cross-sectional dimensions, such as towers and large-diameter pipes and tubes and suppressed-radiation antennas employing such suppressors.

Where such a self-supporting vertical radiator is employed, it becomes necessary, in order to maximize the desired horizontal radiation, to isolate the radiating portion of the antenna from the lowermost portion adjacent the earth or other support upon which the antenna rests. One well-known manner of accomplishing this is to incorporate electrically insulating material as a portion of the structure, thus isolating the radiating and support portions at all frequencies. A simpler method, in antennas designed for particular frequencies, is to incorporate one or more suitable radiation choke structures at the lower end of the desired radiating portion, thus isolating the lower or support portion for the frequencies which are of importance. For this purpose, the present invention provides an improved form of the radiation choke described in co-pending application Serial No. 545,663, filed November 8, 1955, Patent No. 2,896,206 granted July 21, 1959, of the same inventor.

Suppressors and chokes such as discussed above, whether operating on the principles of those disclosed in these co-pending applications or otherwise, are mounted on the mast or tower in longitudinally spaced relation and may of course be individually secured to the mast or tower as protrusions thereon; such individual mounting of these spaced components, however, introduces serious difficulty and expense both in assembly of such a structure and in preserving its rigidity and stability under con-

2

ditions of required use. Where, for example, suppressors are individually mounted, each suppressor must be carefully positioned on the elongated radiator and made the subject of repeated measurements in order to pre-

6 serve the spacing which is of the essence of optimum performance of the antenna. The loosening or loss of rigidity of any single individual mount in use of the antenna will seriously impair its performance. Such difficulties are eliminated in the present structure by the employment of "spacers" between these components, the spacers being conductors extending parallel with the radiating element and acting as radial extensions thereof, the entire assembly of components and spacers being strung in alignment with suitable intervening insulators 15 and rigidly held at both ends to provide a stable and rigid assembly. In addition, in the embodiment of the invention to be illustrated, auxiliary mounts are provided along the length of the assembly of components and spacers, thus assuring minimum effect of the loosening 20 of any single mount on the overall stability of the orientation of the components. In addition, the use of the spacers eliminates the necessity of making elaborate measurements in the assembly of the components to the radiating element and also offers the further advantage 25 that the effective cross-sectional dimensions of the radiating element are increased, thus widening the frequency band of the antenna.

For more complete understanding of the manner of accomplishment of these objects and advantages of the 30 invention, and also of further objects and advantages not yet discussed, reference is made to an embodiment of the invention illustrated in the attached drawing, in which:

Figure 1 is a schematic diagram of an antenna array 35 provided with the suppressor features of the present invention;

Figure 2 is a perspective view of a typical antenna constructed in accordance with the present invention, where 40 in the mast is of triangular cross-section;

Figure 3 is a cross-sectional view as seen in the direction of the arrows along the line 3—3 of Figure 2;

Figure 4 is a detailed view of one of the mounting and insulating support members on one leg of the triangular 45 mast; and

Figure 5 is a detailed view of the antenna sections along one leg of the mast illustrated in Figure 2.

Referring to Figure 1, it will be noted that there has been shown diagrammatically a mast structure 11, which in a physical embodiment comprises a self-supporting structure such as that illustrated in Figure 2. Such structure may be triangular or square, and hence is herein referred to as being polygonal in cross-section. Certain portions of the antenna are arranged to radiate energy, and other portions are arranged to have radiation suppressed therefrom. At the section A the antenna radiation is to be suppressed. Section A is one-half wavelength long. The section B is to radiate energy, and likewise is one-half wavelength long. The next succeeding section C is to have radiation suppressed therefrom. Each 55 of the next two sections D and E is one-quarter wavelength long. The section D has a structure for radiation similar to one-half of section B, and adjacent to section D is the feed portion E to which radiant energy is supplied from a coaxial conductor 12. Immediately 60 below the feed section E there is a radiation section F one-half wavelength long. The overall length of the portions D, E and F is equal to one wavelength. Below the section F is a section G, from which radiation is suppressed, followed by a radiation section H. This in turn is followed by a suppressor section I and a radiation section J. The rest of the lower portion of mast 11 is 65 isolated from those portions A through J by a choke 70

K. While a particular arrangement of radiation sections and radiation suppressors has been shown in Figure 1, this by no means implies a limitation since a greater or lesser number of such sections may be employed dependent upon power to be radiated and the coverage pattern to be produced.

In Figure 2 there is shown a perspective view of a triangular mast 11 which is the equivalent of the mast portion 11 schematically shown in Figure 1. From the cross-sectional view of Figure 3 it will be noted that the mast 11 is formed of three vertical tubular members or pipes 13, 14 and 15 supported in suitable manner by cross-braces 16 extending between the respective corner support rods. Extending outwardly from each of the rods, such as 13, on a line bisecting the angle between two adjacent braces 16, is the structure or structures comprising the suppressed radiation array schematically shown in Figure 1. For convenient reference to the various portions, the same lettering A through K has been applied to Figure 2.

The details of the structures appearing at each of the rods 13, 14, and 15 are more readily apparent from an examination of Figures 4 and 5. In Figure 5 a corner rod support member 15 has been illustrated and carries the various antenna and suppressor sections and feed elements A through J, followed by a choke section K. The section A is supported between two brackets 18 and 19 provided with a plurality of insulating members 21, 22. These insulating members support a rod structure 23 comprising a rod portion 24 extending between the insulators 21 and 22 and joined to two one-quarter wave portions 25 and 26 held in position by a coupling insulator 27. At the ends of the rod 24 suitable connector portions 28 and 29 connect the rod 24 to the portions 25 and 26, respectively. The details of the insulator arrangement for this section A are shown more clearly in the enlarged view of Figure 4. Since it is desired to suppress the radiation from that portion of the mast A for a distance of one-half wavelength, the rod 24 is substantially one-half wavelength long. A simple rod of a length 24 is not sufficient to suppress the radiation, and hence the portions 25 and 26 are provided which have a mechanical length slightly less than a quarter wavelength long. Their effective wavelength relation, however, is substantially that of a quarter wavelength with respect to the rod 24 because of the interconnecting portions 28 and 29. Corresponding portions of the suppressor structures on the pipes 13, 14, and 15 are interconnected by rods 30 to form a cage construction effectively enclosing the mast radiator, only a portion of such interconnecting rods 30 being shown for simplicity of illustration.

The next succeeding section B carries an extended mast surface member comprising a closed loop wire member 31 where the two portions comprising vertical wires 32 and 33 are arranged parallel the same distance apart as the wire portions 24, 25 and 26 of the preceding suppressor section A. The wires 32 and 33 are connected at their ends by portions 34 and 35 to form a complete loop. At the mid-point a conductor 36 is connected to each of the wires 32 and 33 and to the mast member 15 by a clamp 37. From the details of Figure 4 it will be noted that the upper and lower ends of each of the wires 32 and 33 are supported by direct metal contact with fastening clamps 37 and 38 of a bracket 19 so that the wires 32 and 33 are conductively connected radially to the radiating element at intervals of at most one-quarter wavelength to constitute these wires electrically mere enlargements of the radiating element. Connecting wire 35 at the bottom of the structure B is supported by an assembly in which the insulator portions and the clamps are inverted with respect to the assembly at the top so as to support in insulated fashion the next succeeding suppressor section C.

For convenience in understanding the invention, similar reference characters have been applied to those suppres-

sor sections and those extended mast sections which are identical to those portions A and B above described in detail.

The section D is an extended mast section a quarter wavelength long, formed of wire members or rods 41 and 42 connected to a conductor 43 clamped to the mast 15 by a clamp 44. It will be noted that the portion D corresponds to the upper half of the extended mast section 31 of section B. The next portion E, which is a quarter wavelength long, comprises the rods 41 and 42 and a connection 45 to the central conductor of the coaxial line 12. The central conductor of the coaxial line 12 at this point also branches out so as to be connected to the other corner portions E of the other two legs or tubular structural members 13 and 14 of the antenna tower. It will be noted that the bracket 46, which supports the conductive connection 45, is provided with insulator members 47 at its upper side so as to support the conductor 45 in insulated fashion. The bracket 46 conductively connects the upper end of the extended mast portion F to the tubular support member 15.

Below the extended mast surface member J there is located a choke 50 formed of a wire 51 one-half wavelength long connected by bridging portions 52 and 53 to quarter wavelength portions 54 and 55 held in position by a coupling insulator 56. The mid-point of the half-wavelength wire 51 is conductively connected by a connector 57 attached to a clamp 58 surrounding the tubular member 15. It will be noted that the configuration of the wires 51 through 55 has the general appearance of a folded dipole member. This member, because of the mid-point connection to the tower, serves as a choke to preclude the passage of any radiating currents below the extended mast section J, thus isolating the active portion of the antenna from the support portion.

It will be noted that the vertically aligned interspersed elongated conductors and insulators form unitary assemblies of a length of a plurality of wavelengths running parallel with the conducting radiating element, the various conductors having differing electrical connections to provide them with differing effects upon radiation. All of such assemblies are substantially identical and are at substantially identical heights on the tower which in this case, constitutes the radiating conducting element.

Although a single embodiment of the invention has herein been illustrated and described, the application of the teachings of the invention to structures completely different in appearance and details of operation and structure will be obvious. Accordingly, the scope of the protection to be afforded the invention should be determined solely from the appended claims.

I claim as my invention:

1. An antenna comprising a supporting mast having a polygonal cross-section with a vertical conductive member at each corner of the polygon, a plurality of half wavelength radiation suppressors located at alternate half wavelength intervals along each vertical member, the remaining alternate half wavelength comprising radiating portions, each suppressor comprising a shield conductor spaced parallel to said vertical member and insulated therefrom, said shield conductor being connected to two one-quarter wavelength shield conductors spaced parallel thereto, a choke isolating the remainder of said vertical member from those radiating and non-radiating portions, and a feed point intermediate said non-radiating portions.

2. An antenna comprising a supporting mast having a polygonal cross-section with a vertical conductive member at each corner of the polygon, said vertical members being interconnected at intervals by braces, a plurality of half wavelength radiation suppressors located at alternate half wavelength intervals along each vertical member, the remaining alternate half wavelength intervals comprising radiating portions, each suppressor comprising a shield conductor spaced parallel to said vertical member and insulated therefrom, said shield conductor

5. An antenna comprising a vertical member having a polygonal cross-section, a pair of conductors being connected to two one-quarter wavelength shield conductors spaced parallel thereto, said suppressors being located in a plane passing through the vertical member and the center of the polygon, a choke isolating the remainder of said vertical member from those radiating and nonradiating portions, and a connection to a source of radiant energy from said vertical members intermediate two of said radiation suppressors.

3. The antenna of claim 2 having the radiating portions extended radially to the outer shield conductors of said suppressors.

4. The antenna of claim 3 wherein each radiating portion is provided with two parallel conductors connected at their ends and at the midpoints to said vertical member, said conductors being aligned vertically with the shield conductors of adjacent suppressors.

5. An antenna radiation suppressor adapted to shield a half wavelength of an antenna conductor comprising a half wavelength shield conductor arranged parallel to said antenna conductor, a pair of one-quarter wavelength shield conductors extending conductively from the ends of said half wavelength shield conductor toward the center thereof parallel thereto in the plane of said shield conductor and said antenna conductor, the adjacent ends of said quarter wavelength shield conductors producing a high impedance point at the center of said half wavelength shield conductor.

6. The antenna of claim 2 wherein said choke comprises a half wavelength conductor arranged parallel to said antenna conductor and connected at its midpoint to said antenna conductor, and a pair of one-quarter wavelength conductors extending from the ends of said half wavelength conductor toward the center thereof parallel thereto in the plane of said conductor and said antenna conductor.

7. An antenna comprising a polygonal conducting tower of a height of at least a plurality of wavelengths of a signal frequency, each corner having affixed thereto and outwardly spaced therefrom vertically aligned interspersed elongated conductors and insulators forming a unitary linear assembly of a length of a plurality of wavelengths running parallel with the tower, the various conductors having differing electrical connections to provide them with differing effects upon radiation, all of such assemblies being substantially identical and being at substantially identical heights on the tower, and means for feeding a signal to be radiated to at least a portion of the tower.

8. An antenna comprising a polygonal conducting tower of a height of a plurality of wavelengths of the signal frequency, said tower being formed of polygonally arranged conducting poles interconnected by conducting cross-braces, each pole having affixed thereto and outwardly spaced therefrom vertically aligned interspersed elongated conductors and insulators forming a unitary linear assembly of a length of a plurality of wavelengths running parallel with the pole, the various conductors having differing electrical connections to the tower to provide them with differing effects upon radiation, all of such assemblies being substantially identical and being at substantially identical heights on the tower, and means for feeding a signal to be radiated to at least a portion of the tower.

9. An antenna comprising an elongated rigid conducting element of a length of a plurality of wavelengths having mounted thereon, and spaced therefrom, aligned alternated elongated conductors and insulators forming at least three substantially identical unitary linear assemblies of a length of at least a plurality of wavelengths running parallel with the rigid element and dispersed symmetrically therearound, some of said conductors having all portions thereof conductively connected radially to the radiating element at intervals of at most one-quarter wavelength to constitute electrically mere enlarge-

ments of the radiating element and others of said conductors having portions thereof of at least one-quarter wavelength free of radial connection to the rigid element to alter the radiation pattern of the element.

5 10. An antenna comprising an elongated rigid conducting element having an active portion adapted to radiate signals of a given frequency and a support portion, and means for electrically isolating the support portion from the active portion for signals of such frequency including a radiation choke comprising at least three conductive members disposed symmetrically about the element and parallel therewith and each having a substantially half-wavelength portion spaced from and parallel with the element and substantially quarter-wavelength portions spaced from and parallel with the half-wavelength portion and having their outer ends conductively connected to the ends of the half-wavelength portion and the inner ends mutually insulated, the longitudinal center of the half-wavelength portion being conductively connected to the element.

15 20 25 30 35 11. An antenna adapted to radiate signals of a given frequency comprising an elongated rigid conducting element of a length of a plurality of wavelengths having on alternate half-wavelength portions thereof radiation suppressors each comprising at least three conductive members disposed symmetrically about the element and parallel therewith and insulated therefrom and each having a substantially half-wavelength portion outwardly spaced from and parallel with the element and substantially quarter-wavelength portions outwardly spaced from and parallel with the half-wavelength portion and having their outer ends conductively connected to the ends of the half-wavelength portion and their inner ends mutually insulated.

40 45 50 55 60 65 12. An antenna adapted to radiate signals of a given frequency comprising an elongated rigid conducting element of a length of a plurality of wavelengths having on longitudinally spaced portions thereof radial extensions comprising at least three conductive members of one-half wavelength disposed symmetrically about the element and parallel therewith and conductively connected to the element at their ends and their longitudinal midpoint, and a radiation suppressor conductor insulatedly supported by and between said radial extensions to suppress radiation from the corresponding portion of the element.

13. An antenna structure comprising an elongated conducting rigid radiating support and a plurality of folded conducting elements in mutually spaced relation along at least a portion of the length of the radiating member and radially spaced therefrom, the folded elements each being conductors having an inner linear portion and an outer linear portion parallel to the inner portion, said portions being conductively connected at their ends and one of said portions including a central insulator, and conducting spacer and support members insulatedly supporting the elements, each spacer member having inner and outer linear portions aligned with the corresponding portions of the folded elements and having their ends insulatedly joined to adjacent ends of the corresponding portions of said folded elements, the inner and outer portions of each of the spacer members being conductively connected to each other and to the radiating support at intervals of at most one half the length of the parallel portions of the adjacent folded elements, the folded elements being held in said positions by the spacers, and the spacers being held in said positions by their conductive connections, so that the spacer members constitute part of the radiating support at the frequency at which the adjacent folded members are of a half-wavelength.

70 75 14. A suppressed-radiation antenna comprising an elongated radiating conductor having therearound a plu-

rality of longitudinally spaced radiation suppressors forming alternated radiating and suppressed-radiation segments each electrically substantially a half-wavelength long, at least portions of the radiating segments of the conductor between the suppressors being of greater cross-sectional dimension than the segments within the suppressors.

15. The antenna of claim 14 wherein the cross-sectional dimension of said radiating segments is substantially equal to that of the suppressors.

16. The antenna of claim 14 wherein there are provided insulators connecting ends of the portions of greater cross-sectional dimension and adjacent ends of the suppressors, each suppressor being maintained in position by the insulators at each end.
